GRATE

George J. Gorsuch, Rochester, N. Y., assignor of
one-half to Max J. Cohen, Irondequoit, N. Y.

Application March 9, 1935, Serial No. 10,165

4 Claims. (Cl. 126—163)

This invention relates to grates for stoves, furnaces, and the like.

An object of the invention is to provide an improved grate capable of burning small sizes of coal, such as pea coal, buckwheat coal, and the like.

Another object is the provision of a grate of this character which can be easily and quickly installed in existing stoves and furnaces, and which 10 will burn fine coal in an easy manner without the necessity of using a fan or blower.

Still another object is the provision of such a grate so designed that it may be constructed easily and relatively economically.

15 To these and other ends the invention resides in certain improvements and combinations of parts, all as will be hereinafter more fully described, the novel features being pointed out in the claims at the end of the specification.

20 In the drawings:

Fig. 1 is a vertical section through a part of a fire pot showing in side elevation a grate constructed in accordance with a preferred embodiment of the invention;

25 Fig. 2 is a vertical section taken substantially centrally through the grate shown in Fig. 1;

Fig. 3 is a vertical section through a fragment of the grate and associated parts, on a larger scale;

30 Fig. 4 is a perspective view of one of the grate supporting members;

Fig. 5 is a plan of the grate installed in the fire pot;

Fig. 6 is a view of the grate looking upwardly 35 from underneath; and

Fig. 7 is a perspective view of part of a grate supporting ring.

The same reference numerals throughout the several views indicate the same parts.

40 At 10 there is indicated diagrammatically a fire pot of a stove or furnace, this fire pot being of frusto-conical form with its smaller end downwardly, in the usual manner.

According to the present invention, there is 45 mounted at the lower end of this fire pot a ring 11, conveniently made of two semi-circular portions such as shown in Fig. 7, which ring is suitably secured in the fire pot, by resting upon the conical walls thereof or otherwise, and which has 50 an inwardly projecting rim or ledge having a flat top surface 12. The main body of the grate is indicated at 13 and may conveniently be made in two halves which, when secured together by bolts or screws 14, form a somewhat frusto-con- 55 ical member as shown plainly in the drawings.

The bottom edge of this frusto-conical grate might, under some circumstances, rest directly upon the ledge 12 of the supporting ring 11, but it is preferred to elevate it slightly above the ledge 12, resting the grate 13, for example, on a 5 plurality of supporting members 16 each of which has a flat bottom to rest on the ledge 12, and a curved outer edge 17 fitting against the vertical peripheral wall of the ring 11, and sides 18 extending obliquely inwardly at an angle and meeting at a point, as plainly shown in Figs. 4 and 6. Each of these supporting members 16 may also carry an upstanding tooth 19 if desired.

The bottom of the grate 13 is of sufficient diameter to overlap somewhat on the ledge 12, 15 and is supported slightly above this ledge by any suitable number of supporting elements 16, four of such elements being shown in Fig. 6. A pin 19a may extend from each element 16 upwardly into a hole in the bottom of the grate 13, to 20 hold the elements in predetermined position on the grate. The elements 16 are not pinned to the ring 11, however, but are free to slide circumferentially around the ledge 12 on this ring 11 when the grate is shaken, as will be explained in 25 detail hereafter.

The grate itself comprises frusto-conical wall portions tapering upwardly as shown, and provided with a series of circumferential rings or ridges 25 of the shape best shown in Fig. 1. In 30 the grooves between these ridges are air holes 26 which, as shown in Figs. 2 and 3, extend obliquely upwardly and inwardly. Each air hole 26 is protected from entrance of fine coal thereto by means of the overhanging ridge 25 next above 35 it, and also by reason of the sharp upward inclination of the hole itself, which prevents flow of coal any substantial distance into the hole and thus avoids any clogging of the air holes by the fine coal.

40 Any suitable number of such air holes 26 may be provided. Preferably they are arranged in several circumferentially spaced series, the air holes or slots of each series being aligned with each other in a direction up and down the grate, as plainly shown in Fig. 1. These holes permit air within the hollow conical body of the grate to escape through the air holes into the mass of fine coal surrounding the grate, in order to support combustion in the surrounding fine coal.

45 It is found that improved results may be obtained by supplying air also to the coal at various points spaced outwardly from the main body of the grate. To this end, the upper end of the grate is provided with a series of tubes or conduits 50 55

30 communicating with the hollow space within the body of the grate, as shown in Fig. 2, and extending radially outwardly therefrom as shown in Fig. 5. Six such conduits may be conveniently 5 employed, as indicated in the drawings, although obviously the number may be varied depending upon the size of the grate and the kind of coal to be burned. These conduits have outer ends curved downwardly as shown with outlet openings 31 on their under or bottom sides, as plainly indicated 10 in Fig. 2. Air from within the main interior chamber of the grate may pass upwardly into the conduits 30, thence radially outwardly, and be discharged through the outflow openings 31 which 15 are surrounded by coal, so that the air is delivered directly into the body of the coal at some distance outwardly from the main body of the grate and at some distance from the air supplied through the air holes 26. The fire pot is preferably filled 20 with coal to a level some inches above the tops of the conduits 30, the preferred fuel level being indicated diagrammatically in Fig. 1 by the dot-dash line 33. Sometimes it is desired to supply still more air, at a point somewhat above the top 25 of the fuel, in order to promote thorough combustion of any gases rising from the fuel. When such additional air supply is desired, it may be furnished by means of a substantially vertical conduit 35 rising from the center of the top of the 30 main body portion of the grate and extending to a point somewhat above the fuel level 33, where it has an open top covered and protected by a conical hood 36 which prevents coal or other matter from falling into the top of the conduit 35, while 35 nevertheless allowing easy escape of air from the conduit. A damper 37 may be placed in the conduit 35 and may be controlled by the handle 38 to regulate the amount of air flowing through this conduit.

40 In order to promote the flow of air through the lateral conduits 30 and insure delivery of air through them to the coal, it is preferred to construct the grate in such manner that some degree of air pressure will be exerted to drive the air 45 through these conduits. This may be accomplished by the use of baffle means extending downwardly within the main body of the grate for a substantial distance from the conduits 30 and so constructed that air confined by these baffle means 50 has no chance to escape laterally but must rise upwardly and flow out through the conduits 30 or the conduit 35. In the present preferred form of construction, this is readily accomplished by providing air ducts 40 within the side walls of the 55 main conical body of the grate, in alignment with the air holes 26. These ducts 40 communicate with the space inside the grate only through inlet openings 41 at their bottom ends, and the air holes 26 do not extend all the way through the entire 60 thickness of the walls of the grate, but pass only from the ducts 40 outwardly and downwardly to the exterior. Consequently, air for the air holes 26 may easily pass from the inside of the grate through the openings 41 and upwardly through the ducts 40, to escape laterally through the 65 holes 26. But the interior of the grate from the upper edges of the duct inlet openings 41 up to its top, forms, in effect, a pressure chamber, and any air inside the grate, once it passes above the 70 top edges of the openings 41, is no longer able to escape laterally and thus, due to the draft or stack effect produced in the pressure chamber, is forced upwardly to the lateral conduits 30. The damper 37 in the conduit 35, is, of course, so 75 adjusted as to restrict the amount of air passing

through the conduit 35, so that the desired volume of air is forced into the lateral conduits 30 and discharged into the coal at points radially outwardly from the main body of the grate.

For shaking the grate, it may be rotated or oscillated back and forth about its vertical axis, in any convenient manner. For example, a strong rod 50 may extend diametrically across the main body of the grate near its bottom. A broad bar 51 having a hook-shaped end 52 may be inserted through the ash pit door of the stove or furnace and this hook-shaped end may be hooked over and engaged with the rod 50 as indicated in Fig. 2. Then, since the bar 51 is sufficiently broad to provide a substantial bearing on the rod 50 in a direction lengthwise of the rod, the outer end of the bar 51 protruding through the ash pit door may be swung back and forth in a horizontal direction, and its movement will be transmitted through the rod 50 to the main body of the grate, 20 which will oscillate back and forth about its vertical axis, the supporting members 16 sliding circumferentially on the ledge 12 during such movement. The ashes will then drop out through the annular space between the bottom of the 25 main body of the grate and the ring 11. The upwardly projecting parts 19 of the members 16, as they travel circumferentially, will break up and disturb the packed ashes surrounding the lower part of the grate and thus put these ashes in condition to flow readily downwardly and over the ledge 12 into the ash pit. Likewise, the inclined sides 18 of the supporting members 16 will act as cams or deflectors to displace ashes resting on the ledge 12 and to move such ashes inwardly in a 30 radial direction until they drop off the inner edge 35 of the ledge 12.

It is now apparent that a simple grate has been provided which can be readily installed in existing stoves and furnaces by merely taking out the 40 existing grates and setting the new grate in place on a supporting ring 11 of appropriate size. This new grate has given exceedingly satisfactory service in actual use, and operates efficiently with fine coal, such as buckwheat coal, without the necessity of using any fan or blower. It is also apparent that the fine coal can not run accidentally 45 out of the fire pot, because of the overlap between the inner edge of the ledge 12 and the outer peripheral edge of the main grate member 13. The fine coal, or the ash resulting therefrom, is supported on the ledge 12 until the grate is 50 purposely rotated to shake it, whereupon the agitation of the mass above the ledge 12 causes it to run over the edge of the ledge and fall into the 55 ash pit.

I claim:

1. A grate for burning fine coal comprising a hollow body tapered upwardly to provide inclined side walls against which the coal may rest, said walls having openings for outflow of air therethrough, a plurality of separate conduit means extending radially outwardly in different directions adjacent the top of said hollow body to deliver air into coal surrounding and covering said hollow body, and conduit means extending upwardly from said hollow body to deliver air to a point above the top of the coal.

2. A grate construction for burning fine coal comprising a supporting ring having an inwardly projecting circular flange, a plurality of spaced supporting members resting upon and slidable circumferentially on said flange, a hollow grate body resting upon said supporting members and spaced thereby above said flange in overlapping

relation therewith, said body having air holes therein for outflow of air from the interior of said body to the exterior thereof, and means for rotating said body with relation to said supporting ring to shake down ashes.

3. A grate for burning fine coal comprising a hollow body of substantially frusto-conical shape tapered upwardly to provide inclined side walls against which coal may rest, the outer surface 10 of said body having a series of circumferentially extending ridges projecting outwardly therefrom, a plurality of air ducts each opening into the interior of said body near its lower end and extending thence upwardly, and a series of air outlet 15 let openings extending from each air duct to the exterior of the side wall of the body, each air outlet opening extending downwardly and outwardly and opening substantially at the under side of one of said circumferential ridges so as 20 to be protected thereby.

4. A grate for burning fine coal comprising a

hollow body of substantially frusto-conical shape tapered upwardly to provide inclined side walls against which coal may rest, the outer surface of said body having a series of circumferentially extending ridges projecting outwardly therefrom, 5 a plurality of air ducts each opening into the interior of said body near its lower end and extending thence upwardly, a series of air outlet openings extending from each air duct to the exterior of the side wall of the body, each air 10 outlet opening extending downwardly and outwardly and opening substantially at the under side of one of said circumferential ridges so as to be protected thereby, and a plurality of air 15 conduits communicating with the interior of said hollow body adjacent the top thereof and extending radially outwardly to deliver air into the body of the coal at points outwardly from the top of said hollow body.

GEORGE J. GORSUCH. 20
